EYELASH CURLER

Edgar E. Kahn, Mount Vernon, N. Y.

Application November 5, 1932. Serial No. 641,328

11 Claims. (Cl. 132—32)

This invention relates to eyelash curlers.

An object of this invention is to provide an eyelash curler made of a single piece of properly bent and shaped metal which shall be extremely easy to manipulate, and safe in use.

A further object of this invention is to provide a neat and durable eyelash curler of the character described, which shall be relatively inexpensive to manufacture, and practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention.

Fig. 1 is a perspective view of an eyelash curler embodying the invention, illustrating the method of using the same;

Fig. 2 is a cross-sectional view taken on line 2—2 of Fig. 1;

Fig. 3 is a side elevational view of the eyelash curler;

Fig. 4 is a top plan view of the curler shown in Fig. 3; and

Fig. 5 is a front end view of the eyelash curler shown in Fig. 3.

Referring now in detail to the drawing, 10 designates an eyelash curler embodying the invention, shown in position for use in Fig. 1 of the drawing. The curler 10 is preferably made of a single piece of resilient metal, such as round wire stock properly bent and pressed into the shape shown in the drawing. The curler 10 comprises a coiled portion 11 from which there extends a pair of substantially parallel arms 12 and 14. Extending from the upper ends of the arms 12 and 14 are coils 15 and 16, respectively, said coils 15 and 16 being disposed in planes parallel to each other and perpendicular to the plane of the coil 11. Extending from the coil 16 is an arm 17 substantially in alignment with the arm 14, and extending from the upper end of said arm 17, is a prong 18 disposed in the plane of the coil 16 and disposed at an angle of somewhat more than 90° to the arm 17. The prong 18 may be straight and is preferably of concave cross-section to form a substantially semi-cylindrical inner surface 19.

Extending from the coil 15 is an arm 21 sub-

stantially parallel to the arm 17 but about half the length of the latter. Extending from the upper end of the arm 21 is a U-shaped looped portion 22 disposed in a plane perpendicular to the planes of coils 11, 15 and 16, forming a slot 23 receiving the arm 17 which normally engages the curved end 24 of said U-shaped portion. Extending from said U-shaped portion 22 is an arm portion 26 likewise substantially parallel to the arm 17; and extending from the upper end of the arm 26 is a rod or prong 27 parallel to the concave prong 18.

It will be noted that the resiliency of the coil 11 tends to separate the arms 12 and 14 whereby the arm 17 is caused to contact the curved end 24 of the U-shaped loop 22, and the prong 27 is thus maintained in spaced parallel relation with respect to the concave prong 18. The coils 15 and 16 serve as finger rests or handles, and as shown in Fig. 1 of the drawing, said coils may be pressed between a thumb and a finger to press the prong 27 within the semi-cylindrical surface 19 of the prong 18. In use, the eyelashes 30 are placed between the prongs 27 and 18 of the eye curler 10. The coils or handle portions 15 and 16 are then pressed firmly together for causing the lashes to curve. Obviously, any suitable solution may be used on the eyelashes to enhance the curling effect.

It will thus be seen that there is provided a device in which the several objects of this invention are achieved, and which is well adapted to meet the conditions of practical use.

As various possible embodiments of this invention might be made, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. An eyelash curler comprising a member made of a single piece of resilient metal comprising a pair of arms interconnected at one end thereof, said arms normally tending to spring apart and adapted to be pressed together, a prong of concave cross-section integrally formed on one of said arms, and a prong integrally formed on the other of said arms adapted to be received within the concave surface of said first prong upon pressing said arms together.

2. An eyelash curler comprising a pair of arms interconnected at one end thereof, a prong of concave cross-section on one of said arms, and a

prong on the other of said arms adapted to be received within the concave surface of said first prong, and a U-shaped loop on one of said arms and spaced from the connected ends of said arms, forming an elongated slot for slidably receiving the other of said arms.

3. An eyelash curler made of a single piece of bent resilient wire comprising a pair of resilient arms normally spaced apart and interconnected at one end thereof, a straight prong of concave cross-section on one of said arms, and a straight prong on the other of said arms adapted to be received within the concave surface of said first prong upon pressing said arms together.

4. An eyelash curler made of a single piece of resilient metal and having a coiled portion, and arms extending from said coiled portion, said arms being normally swung apart by said coiled portion and being adapted to be pressed together, a prong of concave cross-section extending from said coiled portion, and a prong extending from the other of said arms adapted to be received within the concave surface of said first prong.

5. An eyelash curler made of a single piece of resilient metal and having a coiled portion, and arms extending from said coiled portion, said arms being normally swung apart by said coiled portion, a prong of concave cross-section extending from one of said arms, a prong extending from the other of said arms adapted to be received within the concave surface of said first prong, and handles on said arms adapted to be pressed together for pressing said arms together to increase the torsion of said coiled portion and moving said second prong into said concave surface.

6. An eyelash curler made of a single piece of resilient metal and comprising a pair of arms interconnected at one end and normally tending to swing apart, means for limiting movement of said arms apart from one another, a prong of concave cross-section extending from one of said arms, a prong extending from the other of said arms adapted to be received within the concave surface of said first prong, handles on said arms adapted to be pressed together for pressing said arms together and moving said second prong into said concave surface.

7. An eyelash curler comprising a coiled portion, a pair of substantially parallel arms extending from said coiled portion, a pair of coils at the upper ends of said arms, respectively, disposed in planes parallel to one another and substantially perpendicular to the plane of said first coil, an arm extending from one of said pair of coils, and a concave prong extending from the upper end of

said last mentioned arm, and an arm extending from the other of said pair of coils and having a prong adapted to be received within the concave surface of said first prong.

8. An eyelash curler made of a single piece of resilient metal comprising a coiled portion, a pair of arms extending from said coiled portion, a pair of coils at the upper ends of said arms, respectively, an arm extending from one of said pair of coils, and a prong of concave cross-section at the upper end of said last mentioned arm, a portion extending from the other of said pair of coils disposed substantially parallel to said last mentioned arm, a U-shaped loop extending from said portion and receiving said last mentioned arm therein, a second portion extending from said U-shaped loop likewise substantially parallel to said last mentioned arm, and a prong extending from said second portion and disposed parallel to said first prong and adapted to be received within the concave surface of the latter.

9. An eyelash curler made of a single piece of resilient metal comprising a coiled portion, a pair of arms extending from said coiled portion, a pair of coils at the upper ends of said arms, respectively, an arm extending from one of said pair of coils, and a straight prong of concave cross-section at the upper end of said last mentioned arm, a portion extending from the other of said pair of coils disposed substantially parallel to said last mentioned arm, a U-shaped loop extending from said portion and receiving said last mentioned arm therein, a second portion extending from said U-shaped loop likewise substantially parallel to said last mentioned arm, and a straight prong extending from said second portion and disposed parallel to said first prong and adapted to be received within the concave surface of the latter.

10. An eyelash curler comprising a pair of substantially parallel arms connected at one end, a pair of coils at the upper ends of said arms, respectively, disposed in planes parallel to one another, an arm extending from one of said pair of coils, and a concave prong extending from the upper end of said last mentioned arm, and an arm extending from the other of said pair of coils and having a prong adapted to be received within the concave surface of said first prong.

11. An eyelash curler comprising a pair of arms, resilient means for normally separating said arms, a prong of concave cross-section, on one of said arms and a prong on the other of said arms adapted to be received within the concave surface of said first prong upon pressing said arms together against said resilient means.

EDGAR E. KAHN.
